P. J. KELLY,
AUTOMATIC BOILER CONTROL,
APPLICATION FILED NOV. 26, 1917.

1,315,776.

Patented Sept. 9, 1919.

UNITED STATES PATENT OFFICE.

PATRICK J. KELLY, OF CHICAGO, ILLINOIS, ASSIGNOR TO KELLY CONTROLLER COMPANY, OF CHICAGO, ILLINOIS, A CORPORATION OF ILLINOIS.

AUTOMATIC BOILER CONTROL.

1,315,776.

Specification of Letters Patent.

Patented Sept. 9, 1919.

Application filed November 26, 1917. Serial No. 203,928.

To all whom it may concern:

Be it known that I, PATRICK J. KELLY, a citizen of the United States, residing at Chicago, in the county of Cook and State of Illinois, have invented certain new and useful Improvements in Automatic Boiler Controls, of which the following is a specification.

This invention relates in general to the automatic control of boilers in steam heating systems, and is an improvement on that method of automatic control described in my Patent No. 1,059,302 granted April 15, 1913. In this patent I have provided means operated by flooding of the water when the boiler becomes too hot, commonly termed priming of the boiler, for cutting off communication between the boiler and the pipes of the heating system and for simultaneously closing the damper. Thus, flooding of the mains and radiators and the consequent pounding and hammering is prevented and only dry steam is delivered to the radiators.

In the present invention I have aimed, primarily, to improve this system with the view to more quickly restoring it to normal after flooding of the boiler caused by overheating. This I accomplish by the provision of means actuated by flooding of the water to automatically deliver cold water to the boiler, thus effectually assisting in quickly restoring the system to normal.

Another object of my invention is to provide means for carrying out this system of operation in a simple and practical manner so as to insure satisfactory and reliable action at all times.

Referring to the drawing,

Figure 1 is a side elevation of a heating system embodying my improvements;

Fig. 2 is an enlarged fragmentary view taken substantially on the line 2—2 of Fig. 1, showing the valve and actuating mechanism controlling the delivery of cold water to the boiler for the purpose of restoring the system to normal;

Fig. 3 is a vertical sectional view taken on a median line through Fig. 2; and

Fig. 4 is a horizontal sectional view through the water inlet valve.

The steam heating system shown in the drawing simply as illustrating one example of my improvements, comprises a boiler and furnace designated generally by reference

characters 3 and 4 respectively, adapted for ordinary house heating and for general heating purposes. The boiler receives its water supply through the pipe 5 and steam is delivered through the pipes 6 and 7 into the chamber or trap 8 from whence it passes through the pipe 9 to the various distributing pipes 11 connected with the radiators. The water ordinarily carried over by the steam is trapped in the chamber 8 and flows back through the pipe 12 to the bottom of the boiler, thus keeping the steam dry and preventing too much moisture from getting into the radiators.

When the boiler gets too hot as it sometimes does, the water boils over, flooding the trap 8 and unless instantly checked would pass into the distributing and heating pipes of the system, impairing the efficiency of the system and causing hammering and pounding. I have provided for handling this condition, as described in my patent mentioned above, by the provision of a butterfly valve 13 positioned just above the trap 8 and connected to a float 14 disposed in the trap and adapted to be actuated by the water therein for operating the valve. Should the boiler become too hot and boil over, the water accumulating in the trap 8 causes the float 14 to rise and close the butterfly valve 13, thereby preventing passage of water to the heating pipes. This rising movement of the float is also employed to close the damper 15 so as to cause the boiler to cool down. For this purpose the damper door is connected with the rock shaft 16 to which the butterfly valve 13 is secured, through the intermediary of a suitable connection designated generally by reference character 17. Obviously, when the float rises the shaft 16 will be rocked in a clockwise direction, thereby causing the damper 15 to be closed. When the water in the trap 8 has been returned to the boiler through the pipe 12, the float will lower and again open the valve 13 and also the damper 15. The foregoing system is fully described and claimed in my previous patent and my improvements are incorporated in this system in the manner now to be described.

The present invention consists broadly in adding to this heating system a means actuated by the rising of water in the trap when the boiler primes, for delivering cold water

from the city main or elsewhere to the bottom of the boiler so as to more quickly cool down the boiler and restore the system to normal. The cold water is delivered to the 5 bottom of the boiler through the pipe 18 which receives its supply through the pipe 19. A sliding valve 21 controls the water supply to the pipe 18 and is adapted to be moved lengthwise in the valve casing 22 10 through the agency of a connection with the shaft 16. This connection consists, in this instance, of a lever 23 passing through a slot in the outer end of the valve stem and connected by a link 24 to an arm 25 secured by 15 means of a set screw 26 to the rock shaft. It will be manifest that when the float 14 is caused to rise as previously explained, the shaft 16 will be rocked in a clockwise direction, thus moving the valve 22 lengthwise 20 so as to open the water supply passage, permitting cold water to flow from the pipe 19 into the pipe 18 and thence into the bottom of the boiler. The effect of this cold water delivered to the boiler is to cool the same, 25 so that in connection with the closing of the damper and of the passage between the boiler and heating pipes, as mentioned above, the system will be quickly and effectually restored to normal. With the addition to my 30 automatic trap and damper control, of this means for delivering cold water to the boiler, the operation of controlling the boiler and restoring the system to normal is effected more quickly and satisfactorily than 35 has been heretofore possible.

It is believed that the foregoing conveys a clear understanding of the objects prefaced above, and it should be understood that while I have illustrated one working 40 embodiment of my improvements, various changes might be made in the construction and arrangement of parts without departing from the spirit and scope of the invention as expressed in the appended claims, 45 in which—

I claim:

1. In a steam heating system, the combination with a boiler and the heating pipes of the system, of a trap in the passage between the boiler and heating pipes, and means actuated by the rising of water to a predetermined level in the trap for delivering cold water to the boiler.
2. In a steam heating system, the combination with a boiler and the heating pipes of the system, of means actuated by priming of the boiler for closing the passage between the boiler and said heating pipes and for

substantially simultaneously delivering cold water to the boiler.

3. In a steam heating system, the combination with a boiler and the heating pipes of the system, of a trap in the passage between the boiler and heating pipes, a float in said trap, a valve in said passage adapted to be operated by said float to close the passage, and means operated by said float for causing cold water to be delivered to the boiler when water rises in said trap.

4. In a steam heating system, the combination with a boiler and the heating pipes of the system, of means rendered operative by priming of the boiler to restore the boiler to normal temperature conditions, said means comprising apparatus actuated by rising of the water to a given level for closing the passage between the boiler and heating pipes and for delivering cold water to the boiler.

5. In a steam heating system, the combination with a boiler, the heating pipes of the system and a furnace for the boiler including a damper, of a valve in the passage between the boiler and the heating pipes, a trap interposed between the boiler and heating pipes and adapted to receive the overflow from the boiler, a float in the trap connected with the valve for operating the same, a connection between the float and damper whereby the latter is operated by the former, and means operated by the float for delivering cold water to the boiler, the parts being so arranged that by rising movement of the float the valve and damper will be moved in a closing direction and cold water will be delivered to the boiler.

6. The combination of a boiler, a chamber interposed in the steam supply line therefor, a float in said chamber, a valve adapted to be actuated by said float to close the steam supply line, a water supply pipe to the boiler, a valve interposed in said pipe, and a connection between said valve and said float whereby said water valve is opened as the steam valve is closed.

7. The combination of a boiler, a water supply pipe therefor, a steam delivery pipe therefrom, valves in said pipes, and means for opening the water valve and closing the steam valve upon priming of the boiler.

8. The combination of a boiler, a delivery pipe therefrom, a water supply pipe thereto, and means actuated by priming of the boiler for admitting cold water to the boiler.

PATRICK J. KELLY.
